UNITED STATES PATENT OFFICE.

DANIEL J. MURNANE, OF SAN MATEO, CALIFORNIA, ASSIGNOR, BY DIRECT AND MESNE ASSIGNMENTS, TO MURNANE UNIVERSAL TWIN MIRROR COMPANY, OF SAN FRANCISCO, CALIFORNIA, A CORPORATION OF CALIFORNIA.

WALL-CABINET HINGE.

Application filed November 30, 1925. Serial No. 72,154.

My invention relates to wall cabinets particularly adapted for use in bath rooms, dressing rooms or the like.

One of the objects of my invention is to provide a cabinet embodying double pivotally mounted mirrors which form closures for the cabinet, and which when closed offers a very neat, finished appearance.

Another object of my invention is to provide a cabinet of the above mentioned character, in which the pivotal mountings for the mirrors are disposed entirely within the cabinet when the cabinet is shut.

A further object of my invention is to provide a cabinet of the above mentioned character embodying mountings comprising hinge pivots of simple construction, and which will permit a wide pivotal action of the mirrors so that they may be swung well out from the cabinet, and conveniently adjusted to provide oppositely disposed mirrors in which one may get an all round view of one's person.

My invention possesses other objects and features of advantage some of which, with the foregoing, will be set forth in the following description of my invention. It is to be understood that I do not limit myself to the showing made by the said description, as I may adopt variant forms of my invention within the scope of the claims.

In the accompanying drawings:

Figure 1 is a front elevation of a cabinet constructed according to my invention. A portion of the figure is omitted to reduce its length.

Figure 2 is a plan view of the cabinet shown in Figure 1. One of the doors is shown in closed position and the other door is shown partially extended. Portions of the structure are shown broken away.

Figure 3 is a detail in vertical section taken on the line 3—3 of Figure 1 and showing the catch for maintaining the doors in closed position.

Broadly stated my invention comprises a casing to the open front of which is secured a frame. Mounted so as to normally form a closure for the casing is a pair of mirrors of similar size and shape, and adapted when in closed position, to rest snugly against the front of the frame. The mirrors are pivotally mounted in the casing by means of novel hinge links disposed within the cas-

ing when the cabinet is shut. Each hinge link has a straight body portion extending substantially the width of the mirror, and a pivot at each end of the body portion, extending at right angles thereto in the same direction and offset from the body portion on opposite sides thereof. One pivot is mounted on the frame within the casing adjacent one edge of the mirror, and the other is connected to the mirror adjacent the opposite edge thereof. By this means the mirrors may be swung well clear of the cabinet and arranged opposite each other in various angular relations, so that the user may readily obtain an all round view of his person.

More specifically, my invention comprises a casing 2 preferably of sheet metal and preferably of a size adapted to fit between the studs of a wall. To the open front of the casing is secured, preferably by welding or riveting, a frame of angle iron, which extends around the entire opening of the cabinet. The frame comprises vertical side face members 3 and 4 and horizontal top and bottom members 6 and 7 respectively, all of which combine to make a continuous front for the frame. The vertical members 3 and 4 are formed with flanges 8 and 9 respectively; and the horizontal members 6 and 7 with similar flanges 11 and 12 all of which flanges fit within the front of the casing, and by which means the frame is secured to the casing. Secured to the flanges 8 and 9 are hinge brackets 13, disposed one near the top and one near the bottom of each flange. Each of the brackets 13 is provided with a socket 14 in which is pivotally mounted a hinge link for supporting the casing closure. The hinge-links are all of similar shape and preferably formed of a single length of metal rod. Each of the hinge-links comprises a straight body 16 having arms 17 and 18 disposed one at each end thereof. The arms 17 and 18 are disposed at right-angles to the body 16 and extend in different directions therefrom. The ends of the arms 17 and 18 form parallel pivots 19 and 21 respectively which extend at right angles to said arms, and in the same direction. The pivots 21 seat in the sockets 14 thereby making a pivotal connection about which the hinge links may be swung. A pair of metal box-like frames 22 are pivotally mounted on the free end of each pair of hinge-links, and
